APPARATUS FOR PRODUCING ARTIFICIAL
FOG OR SMOKEThomas S. Derr, Newton, Mass., assignor to
American Steam Automobile Company, West
Newton, Mass., a corporation of Massachusetts

Application January 18, 1943, Serial No. 472,725

3 Claims. (Cl. 252—359)

This invention relates to the production of an artificial fog or smoke for use as a screen or any other purpose, and the principal objects are to provide a method of and means for producing a fog or smoke rapidly, extensively and at a relatively low cost, without risk of fire or explosion and with material which is inexpensive and readily available and which is non-injurious to man and equipment, to start the production of a fog or smoke on short notice, and to produce a fog or smoke of any desired color and quickly to change the color thereof.

Further objects will be apparent from a consideration of the following description and accompanying drawing, wherein the figure is a longitudinal section through what is now considered a preferred form of the apparatus.

According to the present invention the fog or smoke-producing apparatus comprises a series of interconnected nozzles or the like conduits arranged so that each successively discharges into the next succeeding nozzle which is of sufficiently greater size or cross-sectional area to create a zone of reduced pressure separated from the body of the main jet by a zone of turbulence; and each nozzle after the first one is provided with an inlet opening arranged to communicate with the zone of reduced pressure so as to provide an aspirator effect. One or more of the inlet openings may be connected with a supply reservoir or hopper of the material to be dispersed, and one or more of the other inlet openings may be connected with a suitable source of a gaseous diluent such as air, hot flue gases, or the like.

The material to be dispersed may comprise either a high boiling point fluid or a finely divided solid, such, for example, as clay, depending upon whether a fog or smoke is to be produced, the desired effects, etc. Clay and the like naturally occurring mineral substances are preferred in that such material is readily available, inexpensive, non-injurious and capable of being easily reduced to a fine state of subdivision. In any case a gaseous fluid such as compressed air or steam, preferably superheated, is discharged through the first nozzle so as not only to create a zone of decreased pressure which aspirates either the gaseous diluent or the material to be dispersed through the inlet opening of the second nozzle, but also sets up a zone of turbulence effective to break up or disintegrate the aspirated material and entrain it into the main jet which travels through the second nozzle at a relatively high velocity. The same performance is repeated when the jet of the second nozzle dis-

charges into the third nozzle and so on until the last of the series of nozzles discharges into the atmosphere.

The arrangement of the inlet openings for the diluent gases and the material to be dispersed may be varied and will depend upon the character of the material to be dispersed, the particular type of gas or gaseous fluid discharged by the first nozzle and the diluent gas or gases admitted to the other nozzles, and various other factors which will be recognized by those skilled in the art. Although the diluent gas may be aspirated as above noted, other inlets may be provided through which diluent gas may be introduced either under a pressure greater than that within the nozzle provided with such inlets, or by blowing the gas in at a suitable velocity. If desired, a plurality of supply hoppers, each containing a different colored dispersible material, may be connected to one or more of the inlet openings so that any desired color effects may be produced and valves or the like control means may be provided for each inlet opening so that the density of the smoke or fog may be adjusted or varied as desired.

The embodiment herein shown for the purpose of illustration comprises a series of interconnected axially aligned nozzles 1, 2, 3 and 4 arranged so that nozzle 1 discharges into the adjacent end of nozzle 2, the said adjacent end of said nozzle 2 being of greater cross-sectional area than the discharge end of nozzle 1; and nozzle 2 likewise discharges into the nozzle 3 which is of greater cross-sectional area than nozzle 2, etc. Although the dimensional relationship of the nozzles may vary, satisfactory results have been obtained using a nozzle 1 having a bore of the order of $\frac{1}{4}$ " and flaring to about $\frac{3}{8}$ "; a nozzle 2 having a bore of the order of 1"; a nozzle 3 having a bore of the order of $1\frac{1}{2}$ "; and a nozzle 4 having a bore of the order of 2" which may or may not flare outwardly. In any case the size of the discharge end of nozzles 1 to 3 should be sufficiently smaller with respect to the inlet ends of nozzles 2 to 4, respectively, so that a jet, indicated by the straight arrows 5, creates a zone of reduced pressure, indicated by stippling 6, which is separated from the main jet 5 by a zone of turbulence, indicated by the curved arrows 7.

The nozzles 2, 3 and 4 are provided with inlet openings 10, 11 and 12, respectively, each communicating with a zone 5 of reduced pressure, and the inlets are selectively connected by suitable ducts with a source of the material to be dispersed and a diluent gas. Where, for exam-

ple, the nozzle 1 is connected with a supply of superheated steam, for example under a pressure of the order of 250 pounds per square inch, and hot flue gases are to be used as a diluent, the inlets 10 and 12 are connected by ducts 14 and 15 with a supply of flue gas and the inlet 11 is connected to a supply duct 16 formed with a funnel-like end 17 which receives the conical end 18 of a supply hopper 20, the walls or the ends 17 and 18 being spaced to provide a gap 19 so arranged as to provide an aspirator effect. If desired suitable valves 21, 22, 23 and 24 may be provided to control the flow through the nozzle 1 and inlets 10, 11 and 12, respectively.

In order to operate the apparatus to produce an artificial fog or smoke the hopper 20 is first supplied with a dispersible solid material of the desired color, such for example as clay or the like material, and with the valves 22 to 24 properly adjusted, the valve 21 may then be opened to discharge a jet 5 of superheated steam or other gaseous fluid into the nozzle 2, thereby creating a zone 6 of reduced pressure and a zone 7 of turbulence. The zone of reduced pressure is effective to draw in through the inlet 10 hot flue gases, or other diluent, which are entrained with the main jet 5.

Under some conditions the diluent gas entering through opening 10 serves also to increase the capacity or efficiency of the apparatus by enabling a fixed amount of high pressure gaseous fluid to disperse more material than would be feasible if the jet of high pressure gaseous fluid acted directly on the material; in other words, the diluent gas entering through opening 10, under some conditions, makes possible an increase in capacity to disperse material, over what would be the case if the jet discharged from nozzle 1 acted directly on the material without the benefit of the diluent gas.

The jet travels through the nozzle 2 and discharges into the nozzle 3 and a similar action takes place. However, at this stage the jet 5 aspirates the material to be dispersed through opening 11 and the zone of turbulence 7 is effective to break up or pulverize this material so that as it is entrained by the main jet 5 it becomes entirely or almost entirely dispersed therein. As the material in the hopper 20 is drawn through the conduit 16, air is also drawn in through the gap 19 which not only helps to regulate the flow of material through duct 16, but also tends to prevent clogging and thus tends to effect a more uniform introduction of the material into the nozzle 3.

As the jet 5 and its entrained material is discharged into the nozzle 4, more hot flue gases, or other suitable diluent, are aspirated through the opening 12 and these hot gases, or other suitable diluent, not only act to reduce or prevent condensation of the steam upon its emergence into the atmosphere (if steam is used), but also serve to create a greater degree of turbulence within the nozzle 4 than would otherwise occur, and hence are effective to improve the quality of the fog or smoke in that the particles of dispersed material are more thoroughly broken up and more uniformly distributed throughout the moving mass of gas. Finally the jet 5 is discharged from the end of nozzle 70

4 into the atmosphere to form a smoke cloud, the density and volume of which may be varied by proper adjustment of the valves 21 to 24 and the color of which may be varied or changed by introducing an appropriately colored material through the duct 16 into nozzle 3.

With the aforesaid sizes of nozzles and a steam pressure of the order of 250 pounds per square inch and a steam temperature of 600° F. to 700° F., the steam flow being of the order of eight pounds per minute, this apparatus will disperse a fine powdered clay such as bentonite at the rate of ten to fifteen pounds per minute; and on a relatively calm day the apparatus will generate fog at a sufficiently rapid rate to obscure one-half acre to one acre per minute.

While I have shown and described one desirable embodiment of the invention, it is to be understood that this disclosure is for the purpose of illustration and various changes and modifications may be made without departing from the spirit and scope of the invention as set forth in the appended claims.

I claim:

1. Apparatus for producing an artificial fog or smoke comprising a series of at least three interconnected nozzles, the second, and third nozzles being of greater cross-sectional area respectively than the first and second nozzles of the series so that a jet of gaseous fluid discharging from one nozzle into the next nozzle creates a zone of decreased pressure separated from the main jet by a zone of turbulence, the second, and third nozzles having inlets communicating with the zones of decreased pressure, means for introducing a dispersible material through one of the inlets, and means for introducing gaseous diluent through another of said inlets.

2. Apparatus for producing artificial fog or smoke comprising a series of interconnected nozzles arranged so that one discharges into the next of the series, each nozzle receiving the jet discharged from the preceding nozzle being of greater cross-sectional area so that upon the discharge of the jet there is created a zone of decreased pressure separated from the main jet by a zone of turbulence, each of the jet-receiving nozzles being provided with an inlet communicating with the zone of decreased pressure, and supply ducts connected with said inlets for selectively introducing dispersible material and a gaseous diluent into the zones of decreased pressure.

3. Apparatus for producing artificial fog or smoke comprising a series of interconnected nozzles arranged so that one discharges into the next of the series, each nozzle receiving the jet discharged from the preceding nozzle being of greater cross-sectional area so that upon the discharge of the jet there is created a zone of decreased pressure separated from the main jet by a zone of turbulence, each of the jet-receiving nozzles being provided with an inlet communicating with the zone of decreased pressure, a supply hopper for receiving dispersible material connected to one of said inlets, and a duct for introducing gaseous diluent connected to another of said inlets.

THOMAS S. DERR.
